UNITED STATES PATENT OFFICE.

JOHN J. VALLEY, OF CLEVELAND, OHIO, ASSIGNOR TO GENERAL ELECTRIC COMPANY,
A CORPORATION OF NEW YORK.

DESIGN FOR A SHADE OR REFLECTOR.

54,705.

Specification for Design.

Patented Mar. 9, 1920.

Application filed May 10, 1915. Serial No. 27,276. Term of patent 14 years.

To all whom it may concern:

Be it known that I, JOHN J. VALLEY, a citizen of the United States, residing at Cleveland, in the county of Cuyahoga and State of Ohio, have invented a new, original, and ornamental Design for Shades or Reflectors, of which the following is a specification, reference being had to the accompanying drawing, forming part thereof.

My design consists of a surface ornamentation which may be applied to shades or reflectors of various shapes.

In the drawing, Figure 1 is an elevation of one form of a shade to which my invention may be applied.

My design is applied by cutting the lighting glassware so as to produce the ornamentation shown.

I claim—

The design for a shade or a reflector substantially as shown.

In witness whereof, I have hereunto set my hand this 5th day of May, 1915.

JOHN J. VALLEY.
